DESIGN FOR A PIANO

Gardner C. Kavanagh, Rochester, N. Y., assignor
to Aeolian American Corporation, East Roch-
ester, N. Y., a corporation of New York

Application May 18, 1939, Serial No. 85,065

Term of patent 14 years

To all whom it may concern:

Be it known that I, Gardner C. Kavanagh, a citizen of the United States, residing at Rochester, in the county of Monroe and State of New York, have invented a new, original, and ornamental Design for a Piano, of which the following is a specification, reference being had to the accompanying drawing, forming part thereof.

Figure 1 is a front elevational view of a piano showing my new design.

Figure 2 is a top plan view showing the cover in open position.

Figure 3 is a similar top plan view showing the cover in closed position.

In each of the figures of the drawing, the dominant feature of the design is shown in solid lines.

I claim:

The ornamental design for a piano, as shown and described.

GARDNER C. KAVANAGH.
